AERONAUTICAL MACHINE

John Auguste Domenjoz, New York, N. Y.

Application June 13, 1934, Serial No. 730,422
In France August 16, 1932

5 Claims. (Cl. 244—11)

This invention relates to aeronautical machines and in general is a power actuated apparatus of a type to take the place of the observation balloon for military use and consists of an improved design and arrangement, inexpensive in its initial cost and in its operation and which possesses many important advantages over the customarily employed observation balloon particularly as to maneuverability so as to materially improve the safety factor for the pilot and the machine.

An important feature of the present invention consists of an improved motor driven means for obtaining the ascensional force comprising a flexible motive canopy, preferably of fabric and in the general form of a parachute, connected to be operated by a motor to operate in the nature of a flexible piston to produce a power or lifting stroke as the result of suction above and pressure on the air beneath the motive canopy. The canopy is secured at its outer margin to a rigid frame or carrier for the motor and pilot and its central portion is connected to be vertically reciprocated by the motor and is provided with a one-way valve or shutter operative to close on the descending stroke and to open on the ascending stroke of the canopy thus under the action of the motor to create an ascensional force governed by the speed of the motor. The pilot can thus readily control the elevation of the machine by varying the speed of the motor and additional means for vertical maneuvering is provided in the form of a manually operated air valve to permit rapid change of elevation when desired while maintaining the motor speed for prompt checking of the descent upon release of the valve.

Further important features include the provision of a supplemental, readily releasable, parachute to check the descent upon failure of the motor thereby with safety allowing of the use of a motive canopy of lesser diameter than would otherwise be practicable.

The present application is in part a continuation of my pending application Ser. No. 685,276 filed Aug. 15th, 1933.

The foregoing and other important features and advantages of the present invention will be more fully understood by reference to the accompanying drawings wherein like reference characters are applied to the corresponding parts in the several views.

In the drawings:

Fig. 1 is a view in central, vertical section showing my improved machine.

Fig. 2 is a similar view of the motive canopy and associated parts showing the position at the bottom of the power stroke.

Fig. 3 is a plan view of the central portion of the canopy and shutter arrangement.

Fig. 4 is a plan view of the carrier member or wherry.

Fig. 5 is a central, vertical sectional view showing a modified form employing a supplemental parachute carried by the central portion of the canopy.

Fig. 6 is a view in elevation showing the parachute in use and

Fig. 7 is a detail view in plan showing the central member of the canopy thereof.

In the approved construction embodying the features of my invention as shown in Figs. 1 to 4, a rigid carrier is shown comprised of a rectangular wherry 1 housing a driving motor *m* of the internal combustion type and having a compartment 2 for the pilot. The wherry is rigidly connected at each corner, by means of posts or rods 4, with the annulus 5 formed to provide anchoring means for the outer margin of a flexible motive canopy 6, the central portion of which is connected to be vertically reciprocated by the motor *m*. To this end, the fly wheel 8 of the motor is provided with a crank-pin 9 pivotally connected by pitman 10 to vertically movable rod 11 fitted within a vertical bearing of bracket 12 supported at the top of the wherry. The rod 11 is pivotally connected as shown to the tubular extension rod 14 which is pivotally connected at 15 to a central hub of a movable annulus 16; the hub portion as shown being connected by radial spokes 17 to the annulus. Accordingly, operation of the motor will transmit a vertical reciprocating motion to the movable annulus 16 to which the inner margin of the flexible canopy is attached so that the canopy is vertically reciprocated from its inner margin.

The movable annulus 16 is also formed with an upper hub portion 18 supported by radial spokes 19 defining segmental openings 20 adapted to be closed by segmental shutters 21 pivotally supported at 23 on the hub 18 in position to open upon swinging downwardly and inwardly and upon upward movement to close the openings 20 by engagement with the spokes 19 and under surface of the annulus. Each of the shutters is as shown provided with weighted rods 24 affixed upon its upper surface and inwardly curved to obtain a counter balanced and improved shutter action. The hub 18 is also formed as shown with central openings 26 closed by a spring pressed valve 27

to which a cable 28 is attached and carried downwardly within the rod 14 to a point accessible to the operator. The flexible motive canopy 6 is secured to the respective rigid annulus 5 and the 5 movable annulus 16 by means of cables 30 and 31 about which its margins are wrapped and secured. At 32 there is provided a suitable slide bearing for the rod 14 supported upon spoke members 33 and 34 indicates tension connecting wires between 10 the annulus 5 and the wherry.

The flexible motive canopy 6 is formed of a suitable fabric such as rubberized canvas in circular dome contour and of such diameter as required to produce the desired ascensional force 15 when its central portion is vertically reciprocated by the motor, it being understood that upon the upward stroke of the motor and annulus 16 the shutters 21 will open responsive to air pressure from above as shown in Fig. 1 wherein the parts 20 are shown at the end of the up stroke and that upon the downward stroke of the annulus 16 the shutters will automatically close so that upon the downward or power stroke a strong ascensional force is created as a result of suction above the 25 motive canopy and air pressure beneath. Fig. 2 illustrates the position of the parts at the end of the power stroke.

As will be understood from the structure described the elevation of the machine may be 30 readily controlled by the throttling of the motor and for more rapid descent the pilot may at will open the valve 27.

In Figs. 5 to 7, I have shown a desirable modified construction wherein for the purpose of added 35 safety in the event of stoppage of the motor there is provided a supplemental parachute which may be manually released thus to supplement the parachute effect of the motive canopy and accordingly allow of the employment of the 40 canopy of minimum dimensions with full parachute protection. As shown, the supplemental parachute is carried by the movable annulus 16 which is of modified form omitting the valve of the first described structure and having its upper 45 hub portion provided with a cylindrical housing 49 for the supplemental parachute 41 folded in the usual manner with its outer margin connected by cords 42 to the housing at 43 while the inner marginal portion is folded over and into 50 a central tube 44 and connected to an ejector member 45 of tubular form slidably fitted at its bottom portion within a cylinder 47 secured to the lower hub 15 of the annulus. Beneath the ejector 55 member 45 there is positioned a compression spring 48 and the ejector member is held in position against the influence of the spring by a latch 49 from which an operating cable 50 is extended downwardly and accessible to the pilot. The ejector member has pivotally secured thereto at its upper 60 portion at 52 an umbrella like pilot parachute 53 to assist the full ejection of the parachute 41. The top of the housing 40 is normally closed by pivoted flaps 54 pivoted at 55. The movable annulus as shown is further modified by the arrangement of a double series of air valve shutters 65 56-57 pivoted at 58-59 upon the annulus member. In emergency as will be understood the operator releases the latch 49 allowing the spring to upwardly eject the parachute 41 with the pilot 70 parachute assisting as shown in Fig. 6.

My improved machine, as will readily be appreciated, is particularly adapted for military observation with materially increased safety to the pilot as compared to the free balloon and further is advantageous by reason of compactness 75

and portability, is economical as compared to the gas balloon. Its motive canopy is at all times available as a parachute for safety and with the manually controlled valve is active as a balanced 5 parachute for improved control in maneuvering of the machine. As will be understood varied modifications may be made in my improved machine without departing from the invention as defined in the appended claims.

Having described my invention, I claim:

1. An aeronautical machine of the character described comprising a carrier, a motor supported thereby, a flexible motive canopy secured at its outer marginal portion to the carrier and actuating connections from the motor to the central portion of the canopy operative vertically to reciprocate the canopy central portion and air valve means associated with the central portion of the canopy to allow passage of air therethrough during the up-stroke of the actuating connections. 10

2. An aeronautical machine of the character described comprising a carrier comprising a wherry having an outer annulus support connected thereto, a motor supported by the wherry, 25 a flexible motive canopy secured at its outer marginal portion to the carrier annulus and provided at its central portion with a movable annulus member secured thereto, actuating connections from the motor to the central annulus for the 30 vertical reciprocation thereof and air valve means carried by the central annulus to allow passage of air through the canopy upon the upstroke of the actuating connections.

3. An aeronautical machine of the character 35 described comprising a carrier composed of a wherry having an outer annulus member supported thereon in superimposed relation, a motor supported by the wherry, a flexible motive canopy anchored at its outer marginal portion to 40 the outer annulus and provided at its central portion with a movable annulus member secured thereto, actuating connections from the motor to the movable annulus member and said latter member being provided with pivoted shutter valve 45 means to allow passage of air beneath the canopy upon the upstroke of the actuating connections and having a manually releasable valve to provide for upward air passage through the canopy 50 for rapid descent.

4. An aeronautical machine of the character described comprising a carrier, a motor supported thereby, a flexible motive canopy secured at its outer marginal portion to the carrier and actuating connections from the motor to the central portion of the canopy operative vertically to reciprocate the canopy central portion, air valve means associated with the central portion of the canopy to allow automatic passage of the air therethrough during the upstroke of the actuating connections, a supplemental parachute carried by the canopy central portion and manually releasable ejecting means for the parachute, substantially as described. 55

5. An aeronautical machine of the character 65 described comprising a carrier, said carrier consisting of a wherry having an outer annulus member supported rigidly thereabove, a motor supported by the wherry, a flexible fabric canopy secured at its outer marginal portion to the outer annulus and having secured to its central portion a movable annulus member, actuating connections from the motor to the movable annulus member adapted to vertically reciprocate the latter, said movable annulus member being pro- 70

vided with a circular series of openings and pivoted shutters arranged automatically to close the openings on the downward stroke of the annulus, a parachute housing carried centrally of the 5 movable annulus member, a spring housing within the parachute housing, a parachute ejector member slidably fitted within the spring housing,

an ejector spring therebeneath, a manual releasable latch for securing the ejector member, a parachute secured at its outer margin to the parachute housing and at its inner margin to the ejector member and a pilot parachute pivotally secured to the ejector upper portion. 5

JOHN AUGUSTE DOMENJOZ.
